UNITED STATES PATENT OFFICE.

HENRY FRANKLIN BROWNE, OF SWAMPSCOTT, MASSACHUSETTS.

LAST.

No. 837,913.

Specification of Letters Patent.

Patented Dec. 11, 1906.

Application filed July 28, 1906. Serial No. 328,166.

To all whom it may concern:

Be it known that I, HENRY FRANKLIN BROWNE, of Swampscott, in the county of Essex and State of Massachusetts, have invented certain new and useful Improvements in Lasts, of which the following is a specification.

This invention relates to a last for making a shoe having an internal elastic heel-cushion located above the rigid portion of the heel of the shoe instead of forming the tread portion of the heel.

The particular shoe in the manufacture of which my improved last hereinafter described is used has the heel portion of its outer sole offset below the highest part of the shank portion to form the bottom and front wall of a cushion-pocket, the said pocket permitting the insertion of an elastic cushion in the interior of the shoe above the heel, the upper portion of such cushion being substantially flush with the highest portion of the shank of the sole. The said cushion is secured in place against forward and upward displacement by a portion of an inner sole permanently attached to the upper and the outer sole of the shoe, the said inner sole having a two-part heel portion, one part of which conforms to the offset heel portion of the outer sole, and is permanently attached thereto, forming the bottom of the cushion-pocket, while the other part is flexibly connected with the body of the inner sole and forms a displaceable cover for the cushion inserted in said pocket, the cover being movable, so that it may be raised to permit the insertion or removal of the cushion. When the said cover is in place, it conceals the cushion and serves to prevent forward and upward displacement of the same.

The object of the present invention is to enable a shoe having the described internal cushion-pocket to be made on a last, the body portion of which is of the ordinary form and is devoid of an offset heel-seat, so that the last may be used for making a shoe which is not provided with the said internal cushion-pocket.

The improved last in which the present invention is embodied comprises a body portion of ordinary form, and a removable heel-seat extension, one side of which is adapted to bear on the ordinary heel-seat of a last, while its opposite side is adapted to form the offset bottom of the said heel-pocket. The said extension is adapted to be inserted be-

tween the two divisions of the heel portion of the inner sole, and temporarily secured to the last, with the upper division of the inner sole interposed between it and the usual heel-seat of the last, the lower division of the inner sole bearing upon the offset bottom portion of the extension during the lasting and bottoming operations. The heel-seat extension enables the outer sole and the lower division of the heel portion of the inner sole to be permanently connected to each other and to the heel, the upper division of the inner sole being left free from or unattached to the heel portion of the inner sole, so that the said upper division of the inner sole may be raised to permit the insertion of the heel-cushion.

Of the accompanying drawings, forming a part of this specification, Figure 1 represents a sectional elevation of a last embodying my invention, the said last having an inner sole applied to it. Fig. 2 represents a section on line 2 2 of Fig. 1. Fig. 3 represents a perspective view of the heel-seat extension detached from the last. Fig. 4 represents a sectional view showing a modification. Fig. 5 represents a perspective view showing another modification. Fig. 6 represents a sectional view of the heel portion of a shoe made on my improved last.

The same numerals of reference indicate the same parts in all the figures.

In the drawings, 12 represents the body portion of a last, the heel-seat portion of which has the usual relation to the shank and fore part of the bottom of the last—that is to say, the heel-seat portion of the body of the last is not offset in such manner as to form a cushion-pocket in the completed shoe.

13 represents the heel-seat extension, which is preferably a heel-shaped metal piece, the upper surface of which is shaped to have a suitable bearing on the heel-seat portion of the body of the last, while its bottom or outer surface is of such form that when the extension is applied to the last it imparts to the latter an offset heel-seat projecting considerably below the normal heel-seat of an ordinary last. When a shoe is lasted on a last provided with the heel-seat extension 13, the heel portion of the outer sole 15 is offset or depressed below the shank portion of the outer sole. The inner sole, the heel portion of which is composed of the inner member 17 and the outer member 18, is, as above stated, secured to the last prior to

- the lasting operation, the outer member 18 of the inner sole being caused by the extension 13 to assume the same form as the heel portion of the outer sole. The upper of the 5 shoe is applied to the last and secured to the inner and outer soles in the usual manner, the offset-heel portion of the outer sole and the outer member 18 of the inner sole being permanently connected by suitable means, 10 such as the nails which secure the heel 18 to the offset portion of the inner sole. During the lasting operation the inner member 17 of the inner sole remains interposed between the ordinary heel-seat of the last and the 15 heel-seat extension 13. Before the application of the outer sole the fastening device 20, which connects the inner sole and the heel-seat extension 13 to the body of the last, is removed, so that when the last is removed 20 from the shoe the extension 13 will lie loosely in the cushion-pocket which it has formed and may be readily withdrawn therefrom. After the shoe has been removed from the last the extension 13 is withdrawn and a heel- 25 cushion 21, of the same general form as the extension 13, is inserted between the members 17 and 18 of the inner sole, the member 17 being turned upwardly to permit the insertion of the cushion. The member 17 is 30 then turned down upon the cushion, forming a cover therefor and a stop to prevent forward and upward displacement of the cushion. It will be seen that the extension 13 is adapted to form a part of the last during the 35 lasting and bottoming operations and enables the inner member 17 of the inner sole to be kept separate from the outer member 18 during the said operations.
- Means are preferably employed for engaging 40 the extension 13 with the body of the last in such manner as to prevent accidental edgewise displacement of the extension during the lasting operation. The preferred means for this purpose comprises a flange 22 45 on the extension 13, the outer side of the flange being flush with the edge of the extension and fitting a recess or seat 23, formed for its engagement on the body of the last. The extension 13 and the body of the last 50 are thus interlocked, so that the extension cannot swing or slip in any direction upon the last. The fastening device 20, which is driven into an orifice in the extension 13 prevents the extension 13 from moving sideways away from the heel-seat or bottom of 55 the body of the last.
- In Fig. 4 I show a modified form of the flange 22, the said flange being beveled to a thin edge and fitting a correspondingly-beveled face or seat on the body of the last. In 60 Fig. 5 I show instead of the flange 22 a series of studs or dowels 25, adapted to enter sockets formed for their reception in the body of the last. The said dowels are preferably placed at the edge of the extension 13, so 65 that they do not interfere with the inner member 17 of the inner sole. They may, however, if desired, be placed within the margin of the extension, in which case orifices would have to be formed in the inner 70 member 17 for their reception. The bottom surface of the extension 13 is preferably beveled or inclined at its forward end, the inclined portion meeting the upper surface of the extension and forming a thin edge. It 75 will be seen that the last without the extension 13 is adapted for use in making the ordinary type of shoe without an internal cushion-pocket.
- I claim—
1. A last and a heel-seat extension therefor separable from the body of the last.
  2. A last and a detachable heel-seat extension therefor, the last and extension having complementary means for preventing relative 85 movement.
  3. A last and a detachable heel-seat extension therefor, said parts having complementary interlocking members.
  4. A last and a detachable heel-seat extension therefor having a flange adapted to engage the margin of the heel-seat portion of the last-body, the latter having a seat for said flange.
  5. A heel-seat extension having an inner 95 face adapted to bear on the heel-seat portion of a last-body, and an outer face presenting a heel-seat which is offset from said portion.
  6. A heel-seat extension having an inner face adapted to bear on the heel-seat portion 100 of a last-body, and an outer face presenting a heel-seat which is offset from said portion, said outer face being inclined or beveled at the forward end of the extension.
  7. A heel-seat extension having an inner 105 face adapted to bear on the heel-seat portion of a last-body, an outer face presenting a heel-seat which is offset from said portion, and means for engaging said body to prevent displacement of the extension.
  8. A heel-seat extension having an inner 110 face adapted to bear on the heel-seat portion of a last-body, an outer face presenting an offset heel-seat and a marginal flange adapted to engage said body.
- In testimony whereof I have affixed my signature in presence of two witnesses.
